(57) **CLAIM**

The ornamental design for a bread manufacturing machine, as shown and described.

DESCRIPTION

FIG. 1 is a front perspective view showing an embodiment of my new design;

FIG. 2 is right perspective view of the embodiment shown in FIG. 1;

FIG. 3 is a bottom perspective view of FIG. 1;

FIG. 4 is a bottom right perspective view of FIG. 1;

FIG. 5 is a front view of FIG. 1;

FIG. 6 is a back view of FIG. 1;

FIG. 7 is a right side view of FIG. 1;

FIG. 8 is a left side view of FIG. 1;

FIG. 9 is top plan view of the embodiment shown in FIG. 1; and

FIG. 10 is a bottom plan view of FIG. 1;

FIG. 11 is a front perspective view showing an alternate embodiment of my new design;

FIG. 12 is right perspective view of the embodiment shown in FIG. 11;

FIG. 13 is a bottom perspective view of FIG. 11;

FIG. 14 is a bottom right perspective view of FIG. 11;

FIG. 15 is a front view of FIG. 11;

FIG. 16 is a back view of FIG. 11;

FIG. 17 is a right side view of FIG. 11;

FIG. 18 is a left side view of FIG. 11;

FIG. 19 is top plan view of the embodiment shown in FIG. 11; and,

FIG. 20 is a bottom plan view of FIG. 11.
